UNITED STATES PATENT OFFICE.

RUBY W. NEEDHAM AND JEW I. WAGONER, OF GREENSBORO, NORTH CAROLINA.

ATTACHMENT FOR SEPARABLE BUTTONS.

Application filed March 23, 1925. Serial No. 17,742.

The purpose of the invention is to provide a device to be used with buttons of the character wherein a threaded stud is provided on one member and a securing nut threadingly engaged with the stud, so that the nut will be insured remaining in attached position and the protruding end of the stud guarded to preclude its wearing a hole in the apparel.

With this purpose in view, the invention consists in a construction and combination of parts of which a preferred embodiment is illustrated in the accompanying drawings, wherein:

Figure 1 is an edge elevational view showing a separable button with the device attached.

Figure 2 is a central vertical sectional view through the structure of Figure 1.

Figure 3 is a front view of the device.

Figure 4 is a rear view.

Figure 5 is an enlarged sectional view similar to Figure 2, the button, however, being shown in elevation.

Figure 6 is a sectional view on the plane indicated by the line 6—6 of Figure 1.

Designed for use in connection with buttons particularly of the emblem form, such as that indicated at 1 in the drawings, the invention serves as a means for precluding retrograde movement of the nut 2 when attached to the stud 3 with which it is threadingly engaged. The device consists of a cap 4 of elastic material and serving to completely enclose the nut 2 with which it

is engaged by stretching it over the nut, the latter entering the cap through the central opening 5 on the front face of the latter.

When attached, the front face of the cap bounding the opening 5 engages the rear face of the lapel 6 or other portion of the garment to which the button is attached and its frictional contact prevents turning of the cap, the adherence of the cap to the nut preventing relative turning movement between the two. At the same time the rear wall of the cap acts as a protector to shield the protruding extremity of the stud 3 and thus prevents its wearing a hole in the garment.

The invention having been described, what is claimed as new and useful is:

In combination with a button having a stud for penetration through a piece of wearing apparel, a nut threadingly engageable with the stud at the remote side of the apparel, and a cap enclosing the nut and formed with an opening for the passage of the stud, the cap being of a material having a high coefficient of friction and the peripheral edges bounding said opening engaging the apparel within the area covered by the button, the rear face of the cap serving as a shield for the inner end of the stud.

In testimony whereof they affix their signatures.

RUBY W. NEEDHAM.
JEW I. WAGONER.
